COKE OVEN WITH GAS RECIRCULATING MEANS

Joseph van Ackeren, Pittsburgh, Pa., assignor to
 Koppers Company, Inc., Pittsburgh, Pa., a corporation of Delaware

Application November 8, 1945, Serial No. 627,378

8 Claims. (Cl. 202—109)

1

This invention relates to the control of the temperature in the gas space at the top of a coke oven. More particularly the invention relates to a mechanism for controlling the flow of gas through the gas spaces above the coal being carbonized in a coke oven, and through gas collecting mains to maintain a predetermined maximum temperature in the gas space at the top of the coke oven.

It is very desirable to maintain a substantially uniform temperature from the bottom to the top of a coal bed in a horizontal coke oven that is being carbonized to produce coke. Heretofore some coke oven designs have arranged the top of the heating flues at each side of the coke oven to be below the top of the oven carbonizing chamber in order to prevent overheating of the gas space at the top of the oven. Even with low top heating flues it is often difficult to prevent overheating the gas space at the top of the oven because some coal shrinks so much that the top of the coke bed falls below the top of the heating flues. In case the tops of the heating flues are below the normal top of the coal bed being coked, the gas space above the fuel bed may become overheated if the temperature in the heating flues is raised sufficient to increase the rate of coal carbonization. Overheating the gas space acts to crack hydrocarbon vapors, and ammonia which are formed by the coal carbonization and thus crack all or a part of the byproducts to decrease the value of the byproducts obtained. Such a cracking operation also acts to form carbon which builds up on the walls of the oven and more especially in the gas space interferes with the heat transfer and the proper carbonization of the coal.

The primary object of the present invention is to provide a method and apparatus for controlling the temperature of the gas and vapor in the space at the top of the coke oven while permitting the maintenance of any desired temperature in the coke bed.

One important feature of the present invention is to cool the gas being made and maintain a positive circulation of cool gas through the gas space at the top of the oven. The oven is approximately 40 feet long so that when a cold gas enters at one end of the gas space of the oven

to pass through the oven, the temperature of the gas is raised to nearly the temperature of the coke bed before the gas leaves the other end of the oven. To avoid this condition the direction of flow of the cold gas is reversed at frequent intervals in order to bring the cold gas alternately into the opposite ends of the oven and to maintain a substantially uniform temperature throughout the length of the oven space.

10 Accordingly another object of the invention is to maintain a positive circulation of cooled gas through the gas space of the ovens in alternating directions to maintain a substantially uniform temperature in the gas space at the top of the oven.

15 A further object of the invention is to provide a method of controlling the temperature in the top space of a coke oven by cooled gas which is saturated with water to have a high thermal capacity.

20 A still further object of the invention is to provide a large volume of cooled gas for circulation through the gas space at the top of an oven and to provide a positive flow of a sufficient volume of gas to maintain a uniform temperature throughout the length of the gas space at the top of an oven.

25 With these and other objects and features in view, the invention consists in the improved method and apparatus for controlling the temperature in the gas space at the top of a coke oven hereinafter described and particularly defined in the claims.

30 The various features of the invention are illustrated in the accompanying drawings in which—

35 Figure 1 is a view in elevation with parts shown in section illustrating the application of the present invention to the gas collecting mains of a horizontal byproduct coke oven; and

40 Figure 2 is a diagrammatic top plan view illustrating the connection of the offtake mains to the collecting mains of the coke oven for the purpose of controlling the flow of gas through the space at the top of the coke ovens.

45 The present invention is illustrated as applied to a coke oven of the type illustrated in the patent to Becker 1,752,363 granted April 1, 1930. The coke oven is preferably a horizontal coke oven in which the ovens are arranged side by

side with heating flues on the opposite sides of each oven. A battery of ovens is usually composed of a large number of ovens which are operated as a unit, each of these ovens being connected with common gas offtake mains for recovering the gas distilled out of the coal being carbonized. The ovens are charged to a predetermined level with coal, then carbonized and then the coke pushed out of the ovens in a predetermined time cycle or sequence and thus successively, and only at the time that the coke is being pushed out of an oven are the connections of the oven with gas mains cut off.

Referring to Figure 1 a coke oven 10 is illustrated with doors 12 and 14 mounted at opposite ends. The oven is charged with coal through charging openings 16 and the top of the coal bed is levelled by a levelling bar which is inserted through an opening 18 in the door 12. The space between the top of the oven and the top of the fuel bed is the gas space 11. The heating flues are located between the ovens and these heating flues are heated while a coke oven battery is in operation. As the gases are formed by the coal carbonization they rise through ascension pipes 20 or 22 in accordance with the method of operation of the oven. The gases flowing up through the ascension pipes pass downwardly through a section of the ascension pipe into collecting mains 24. As the gas enters the collecting mains it is met by a spray of ammonia liquor which is introduced through spray pipes 26, which act to cool the gas to a temperature of approximately 80° C. The gas at this time is thus saturated with water and has a high thermal capacity. The amount of spray cooling is, of course, varied to vary the temperature and saturation of the gas and thus control its temperature, as is conventional. From the collecting mains the gas flows through offtake mains 28 to a T 30 and passes through a pressure control valve 32 to a suction main 34. The valve 32 is controlled by a pressure-responsive mechanism 36 which operates the valve in order to maintain a predetermined pressure in the collecting mains. To accomplish this, pressure responsive tubes 38 and 40 pass from the control mechanism 36 to the top of the collecting mains 24. Valves 42 and 44 are mounted in the tubes 38 and 40 respectively to open and close the tubes in accordance with the direction of flow of gas through the offtake mains, according to the present invention, in order to control the flow of gas from one or the other of the collecting mains to maintain the desired pressure in that main as will be hereinafter described.

The carbonization of coal in the coke oven is preferably carried out in the temperature range of 1000° to 1100° C. within the coke bed. To maintain this temperature in the coke oven, the temperature in the heating flues may be 150° to 400° higher in order to drive the heat through the oven walls and through the bed of coal being carbonized. Depending upon the length of time that the coal has been heated to a carbonizing temperature and the temperature of the heating flues, the temperature in the gas space at the top of the coal bed may vary from 750° to 925° C. During the first hour of coal carbonization the largest volume of gas is driven out of the coal. Then the volume of gas being generated during each of the following hours gradually decreases, the usual cycle of coal carbonization being sixteen or eighteen hours between charging coal to the oven and pushing coke out of the oven.

In a typical test on two ovens it was found that the gas generated during the first hour was approximately 10,000 cu. ft. and the gas generated during the sixteenth hour was 4,700 cu. ft. The B. t. u. value of the gas generated gradually decreases during the carbonization of the fuel, and, in the test above referred to, the B. t. u. value varied from 668 B. t. u. per cu. ft. during the first hour to less than 400 B. t. u. per cu. ft. at the end of a cycle.

The analysis of the gas includes the determination of the carbon dioxide, the illuminants which include hydrocarbons having more than one carbon atom to the molecule and composed principally of ethylene, oxygen, carbon monoxide, hydrogen, methane and nitrogen. The carbon dioxide in the gas gradually decreases as the coal is carbonized. The illuminants decreased in the example described above from 6% to 0% at the end of the coking cycle. The oxygen content decreased from 0.4 to 0%. The carbon monoxide decreased from 6% during the first hour to 3.9% during the sixteenth hour and then increased to 6.3% during the eighteenth hour. The hydrogen increased from 44% during the first hour to 84% during the eighteenth hour. The methane decreased from 36% during the first hour to approximately 4% during the eighteenth hour. The nitrogen decreased from 5.7% during the first hour to 2.3% during the fourteenth hour and then increased to 5.6% during the eighteenth hour. The tars are driven off most rapidly during the first four hours of the coking operation. These tars contain phenols, cresols, pyridine, anthracene, anthracene oil and pitch, the products being separated by distillation. The light oils are contained principally in the illuminants and are composed of benzol, toluol and xylol, if the carbonization is carried on at a temperature of 1000° to 1100° in the coke bed. The amount of paraffins in the light oil is usually less than 5% with most coals if the coal carbonization temperature is maintained above 1000° C. At temperatures above 1000° C. most of the hydrocarbons of carbonization are aromatic.

The data given above relates to the treatment of a specific type of West Virginia coal when treated in two different ovens of the same battery wherein the oven walls were maintained at an average temperature of approximately 1300° C. at the pushing side of the oven and 1350° C. at the coke discharge side of the oven. It will be understood that these data would vary for different coals and for different temperatures maintained in the coking chamber. However, the data are representative of the conditions which usually exist in coke ovens.

From the above data it will be seen that the volume of gas and the chemical constitution of the gas being made from hour to hour will vary. It will also be seen that, as the ovens are, as is above pointed out, charged in a predetermined sequence, in the series or battery of ovens thus sequentially charged, the battery or series comprises as conventional, ovens operable concurrently at different stages of carbonization, early, intermediate, and later. Also the carbonization of the coal in a large number of different ovens will give a widely varying condition of gas pressures and quality of gas in each of the spaces above the coking charges in the coke ovens. To maintain a more nearly uniform temperature in the gas space and to hold the temperature thereof at levels lower than would otherwise ob-

tain so that the hydrocarbons and ammonia products will be less decomposed, the present invention contemplates circulating sufficient cooled gas, whose temperature and saturation with water is varied, as conventional as described aforesaid, through the gas-collecting space to control the temperature. Since the gas-collecting space is approximately 40 feet long, the cold gas becomes heated in passing through the gas-collecting space of the oven, and therefore it is important to reverse the direction of flow of gas through said gas-collecting space, and to introduce cold gas at opposite ends of the ovens alternately to assist in getting a more nearly uniform temperature throughout the length of the gas-collecting spaces of the ovens.

The control of the temperature in the gas-collecting crown space may be carried out as follows:

A fan 46 is mounted in the offtake main 28 at the left side of the oven, viewing Figure 1. When this fan is put into operation, it tends to draw cooled gas from the offtake main 28 and force it down into the collecting main 24 and from that collecting main through the ascension pipes 20 into the left hand end of the gas crown-spaces of the ovens in the battery. The volume of gas moved by the fan 46 is sufficient to fill into the collecting main 24 and to force gas through all of the gas crown-spaces above charges in the ovens in the battery. The volume and pressure of the gas maintained in its main 24 by the fan 46 depends upon the size and speed of rotation of the fan and the adjustment of the damper 32 in the T 36. The speed of rotation of the fan is controlled by a variable speed motor or with a variable speed drive between the motor and fan. At the time that the fan 46 is in operation, the valve 44 in tube 40 is held in a closed position so that the pressure-responsive operating mechanism 36 will control the valve 32 in accordance with the pressure as indicated from the tube 38 in the left hand collecting main 24. The collecting mains 24 have a sufficiently large volume so that the pressure along substantially the entire length will be substantially uniform and thus supply gas to the ascension pipes of each of the ovens with a uniform pressure. It will be understood, however, that the gas pressure in the gas spaces at the top of each of the ovens will vary somewhat in accordance with the state of carbonization being carried on therein and, therefore, the oven which is generating the smallest volume of gas will receive the largest volume of cooled gas from the collecting main 24. This condition is very desirable because the ovens which are generating the smallest volume of gas generally have the coke bed at the highest temperature and, therefore, a larger amount of cooled gas is required to maintain the desired temperature in each of the gas spaces above the coke beds. Furthermore, the temperature of the gas space in the top of the ovens in which the carbonization has just started is lower than in the ovens where the carbonization is more complete and, therefore, a comparatively small amount of cooled gas will pass from the collecting main into the ovens generating the largest volume of relatively cooler gas. Yet, it will be appreciated from the foregoing that, with such unidirectional flow of cooled gas under positive pressure of fan 45, into the ovens in all of the different concurrent stages of carbonization, early, intermediate, and later, the flow through the gas flow spaces of each oven chamber, of

this additional cooled gas under positive pressure, maintains a rate of flow of gas through each of the gas flow spaces of ovens in all stages of carbonization to the other collecting main, that is then operable for gas off-flow, that is greater than the highest rate of flow of gas caused by the generation of gas by carbonization of coal in any of the ovens.

At the time that coke is being pushed out of an oven the ascension pipes for that oven are cut off from the collecting mains 24 by means of dampers 48 which may be moved manually into closed position. At the time that the oven doors are inserted in the oven and coal is being charged into the oven, the valves 48 are opened to allow the gas to move from the gas space into the collecting mains.

Since the cooling effect of the cooled gas being circulated through the tops of the ovens is soon dissipated by the temperature of the oven bed, it is necessary to frequently reverse the flow of gas and introduce the cooled gas at the opposite end of the gas space from which it formerly was introduced. To accomplish this, a timing device 50 which is any of the well known clock timing devices, is arranged to operate a switch 52 for the purpose of controlling the electric circuit 54 for operating the fan 46 and an electric circuit 56 for controlling the operation of a fan 58 mounted in the right offtake main 28. In accordance with the setting of the timing mechanism the fan 46 will be held in stationary position when fan 58 is operating and fan 46 will be held in stationary position when fan 58 is operating. When fan 46 is operating, the gas drawn from the offtake main 28 and forced into the collecting main 24 to pass through the ovens, the gas will then flow to the collecting main 24 at the right in Figure 1, and then through the offtake main 28 to the T 30 and out through the suction main 34. At this time, the fan 46 will cause to move through the gas-collecting spaces more gas than is being generated in the battery of ovens and so that, that part of the gas it supplies is gas that is recycled for the purpose of controlling the temperatures in the gas spaces above the ovens. The amount of gas released from the offtake mains 28 during these operations is controlled by the valve 32, which is controlled by the pressure in that collecting main 24 which is supplying gas to the then inlet side of the gas spaces above the oven charges.

In practice, it has been found that the direction of flow of cooling gas through the gas space above the ovens should be reversed at about five minute intervals. These intervals, however, may vary quite widely, that is from two minutes to sixty minutes, depending upon the type of coal being carbonized, the type of coke being made, and the type of gas being produced. It is quite desirable, however, to secure the maximum amount of byproducts and, therefore, the reversals are made sufficiently frequent that at the rate of flow and temperature, the temperature of the cooled make-gases is sufficiently low to maintain a temperature in the gas flow spaces at the tops of the coke oven chambers below a maximum of 850° C. to hold the temperature in the gas spaces above the coke beds in the ovens at about 800° C. in order to prevent decomposition of the byproducts being made that otherwise would obtain at higher temperatures.

The use of fans 46 and 58 acts to increase the rate of flow of gas through the gas spaces above the oven charge and thus not only tends

to minimize the cracking or destruction of valuable byproducts but acts to minimize the amount of secondary reactions which take place to form less desirable byproducts.

The timing device 50 which controls the switches for operating the driving motors for the fans 46 and 58 also operates a switch 60 that controls circuits 62 and 64 by which the valves 42 and 44 are opened and closed. It will be understood that with this arrangement, when valve 42 is open, valve 44 will be closed and vice-versa.

As illustrated in Figure 2, the offtake main 28 and suction main 34 are preferably mounted on the collecting mains 24 near their mid portions, so that the gas re-cycled by means of fans 46 and 58 may be introduced into the collecting mains in the central portion more easily to distribute gas throughout the length of the main. Although the ovens are generally arranged in batteries of from thirty to eighty ovens, the number of offtake mains may be varied in order to secure the proper distribution of the cooled gas in the collecting mains for the purpose of controlling the temperature in the gas-collecting spaces at the top of the ovens.

In the drawings, fans 46 and 58 have been illustrated for the purpose of circulating the cooled gas. In some cases it is more desirable to use positive pressure blowers where a large volume of gas is used and such positive pressure blowers would be mounted in a bypass in the offtake mains 28 in order to provide a path for free circulation of the gas when the blower is not in operation. The fans are very advantageous in that when the fan is idle the gas being generated can pass through the fan to the suction main.

The preferred form of the invention having been thus described, what is claimed as new is:

1. The combination with a battery of horizontal coke ovens, each oven having a horizontal gas collecting crown space along the length of the top of the oven; an ascension pipe at each end of each crown space; a collecting main running along each side of the battery and each in simultaneous open communication with the aforesaid ascension pipes located on its side of the battery; an offtake main simultaneously in open communication with each collecting main; a suction main in communication with the offtake main, said suction main continuously withdrawing part of the coke oven gas from said offtake main; gas circulating means for forcing the rest of the coke oven gas from said offtake main back into the collecting main on one side of said battery into all of the connecting ascension pipes, through the open crown spaces of all ovens undergoing carbonization where it joins with any gas being evolved in the coke ovens, all of the gas then flowing out through the ascension pipes and into the collecting main on the other side of the battery, and back into the offtake main; means for reversing the forced gas flow so as to similarly pass the gas through the crown spaces of said ovens in the opposite direction of flow, said reversing means operating periodically so as to have the gas flow in one direction for a suitable predetermined time and then flow in the other direction for a suitable period of flow.

2. Coke oven apparatus comprising, a horizontal coke oven battery; two mains situated at opposite ends of the oven chambers of said battery; each of the ovens operable for concurrent carbonization in the battery being in simultane-

ous open communication at the opposite ends only of the ovens with both of the two mains, and through communication of all of their horizontal gas-collecting spaces at the tops of the oven chambers; gas offtake means for withdrawing combustible gas off from both of said mains; and means for introducing a gaseous cooling medium from a source outside the oven chambers, and under positive pressure, alternately into one and then into the other of the two mains in the direction, and in a manner, for flow into the upper horizontal gas-collecting spaces of said ovens at one end only for flow of all of the cooling medium directly into the same and thence clear across all of the crown spaces to the opposite end, to periodically reverse the direction of flow, with inflow of cooling medium from the outside source into, and outflow of the made-coke oven distillate gas to the gas offtake means from, the respective mains in alternation with each other, and solely by means of the introduction under positive pressure of the cooling medium alternately solely into one and then solely into the other of the two mains, and in which the two gas mains are in open communication with each other through the gas offtake means, and in which the means for introducing said gaseous cooling medium from a source outside the oven comprises separate gas circulating means in the offtake means for circulating part of the gas therein back into the oven chambers through the respective gas mains in alternation with each other.

3. Coke oven apparatus as claimed in claim 2, and which includes valve means for controlling the release of the gas from the gas offtake means, and pneumatic-pressure controlled operating mechanism operatively connected with the two gas mains and with said valve means for periodically controlling the latter in alternation, by and in accordance with the pressure in one end and then the other of the two mains, in conformity with the periodic reversal in flow and in function of the two mains.

4. Coke oven apparatus as claimed in claim 2, and which includes automatic time-controlled means operatively connected with the separate gas circulating means for operating them periodically in alternation with each other.

5. Coke oven apparatus as claimed in claim 3, and which includes automatic time-controlled means operatively connected with the separate gas circulating means and with the pneumatic-pressure controlled operating mechanism, for operating the separate gas circulating means periodically in alternation with each other, and for periodically operating the pneumatic-pressure controlled mechanism.

6. Coke oven apparatus as claimed in claim 2 and in which the gas circulating means is a motor-operated fan.

7. Coke oven apparatus as claimed in claim 2, and in which each of the gas circulating means is a positive-pressure motor driven blower mounted in a by-pass in the gas offtake means, to provide a path for free circulation of the gas when the blowers are not in operation.

8. Coke oven apparatus as claimed in claim 2, and which includes an operating mechanism for the valve means, which operating mechanism is connected with the pneumatic pressure mechanism to be operated thereby by means of the pressure within the main into which the gaseous

2,541,794

9

cooling medium is forced by the gas circulating means.
